UNITED STATES PATENT OFFICE.

CHARLES T. LORING, OF BOSTON, MASSACHUSETTS, ASSIGNOR TO THE ADJUSTABLE TELEPHONE SUPPORT COMPANY, OF SAME PLACE.

TELEPHONE-SUPPORT.

SPECIFICATION forming part of Letters Patent No. 281,381, dated July 17, 1883.

Application filed March 12, 1883. (No model.)

To all whom it may concern:

Be it known that I, CHARLES T. LORING, of Boston, in the State of Massachusetts, have invented a new and useful Improvement in Telephone-Supports, of which the following is a specification.

My invention consists in combining on the same support which holds the receiver of a telephone a support which holds the transmitter in such position relative to the receiver and in such manner that both receiver and transmitter can be placed and held by their supports in such positions relative to the operator that he can use them both without material changing from any position which may be convenient for the use of either. For this purpose I attach to the supporting-standard two arms, one of which holds the receiver at a level convenient for the operator's ear, the other the transmitter convenient to his mouth, and which are adjustable horizontally for regulating the size of the angle they contain to permit the receiver and transmitter to be placed by the operator in positions convenient for his use.

The accompanying drawings illustrate my said invention.

Figures 1 and 2 show the supporting-standard A, having its upper portion bent over and branching into two arms, of which B holds the receiver and is formed by requisite curvatures (or, in lieu of which, joints may be used) to place the receiver at its proper height as respects the transmitter. The other arm, C, supports and holds the transmitter. The two arms are movable by swinging horizontally on a pivot at the joint d, where they branch from the standard A. Both receiver and transmitter are movable longitudinally on the arms

which respectively carry them, and which are 40 interchangeable in position on the joint d (preferably a rule joint) to permit the receiver to be placed on either side of the transmitter. I also provide the posts p p, for the purpose of supporting and holding in position the receiver-wires, near the points where said wires are connected with the telephone-cords, as shown in Figs. 1 and 2.

Fig. 3 shows a vertical section of joint d in front of the standard A and its arm B.

Fig. 4 is a top plan view of the joint d, and shows, also, the posts p p on the bent-over portion of the standard A, and the end of arm B in place in said joint.

I claim as my invention—

1. A telephone-support having two arms, for the purpose set forth, in combination with a receiver and transmitter, and suitably adjusted as to their relative heights and adjustable horizontally, for the purpose and in the manner described.

2. A telephone-support consisting of the support A and arms B C, adjustable in a horizontal plane, in combination with the transmitter and receiver adjustably mounted on 65 said arms, substantially as and for the purpose set forth.

3. In a telephone-support, the arm B and the posts p p, in combination with a telephone-receiver and the wires thereof, as shown and 70 described, for the purpose set forth.

In witness whereof I have signed my name to this specification in the presence of two attesting witnesses.

CHARLES T. LORING.
